UNITED STATES PATENT OFFICE.

CHARLES J. McCABE, OF BROOKLYN, AND IRVING SCHOENHOLZ, OF FAR ROCKAWAY, NEW YORK, ASSIGNORS TO McCABE AND SCHOENHOLZ, INC., OF NEW YORK, N. Y., A CORPORATION OF NEW YORK.

HAND BAG.

Application filed June 9, 1926. Serial No. 114,707.

Our present invention relates to hand bags and has particular reference to women's bags of the type which is carried about day by day.

5 It is an object of the invention to provide a bag of this character wherein the structural components are so shaped and associated that the bag will retain its shape for a considerably longer period of time than 10 the bags of usual construction.

Where we have attempted to construct bags by the association with side elements of a bottom element consisting of a single blank of material, we have found that 15 extensive use will cause the bag to lose its shape by virtue of the fact that the bottom element will stretch and distort. This is particularly likely to occur where the bag is subjected to frequent use, and where the 20 contents are of a character to form a bulky mass which stretches the bag in all directions. This latter condition is almost universally the case in bags of this character, and the bulkiness of the contents will cause 25 the bottom of the bag to stretch and consequently to sag. When this has once occurred, it is extremely difficult for the bag to regain its original form.

It is an object of the present invention 30 to overcome this defect in bags of this character, and more particularly, it is our object to provide a bag wherein this excessive distortion and sagging of the bottom will be prevented.

35 Another object of the invention is to provide a structure which renders it possible to produce a desired configuration with great accuracy and ease, thereby making it possible to produce a finished article having 40 greatly enhanced qualities of appearance and workmanship.

A feature of our invention lies in providing a bottom of composite structure, i. e., 45 constituted of more than a single blank of material. In a preferred construction, we form the bottom by associating two separate strips of material, these strips being so configured that their mutual association will provide the desired contour.

50 Another feature of the invention lies in providing a longitudinal rib for the bottom of the bag, this rib serving to reinforce the bottom in a manner which will limit the extent to which the bottom may sag. In

a preferred construction, this rib is provided 55 by the seam which associates the two component parts of the bottom with each other.

It is an object of the invention to provide a bag which will have extremely good wearing qualities, which will present a neat, 60 workman-like appearance, and which is constructed in a manner which renders the manufacture both simple and inexpensive.

For the attainment of the foregoing objects and such other objects as may herein-after appear or be pointed out, we have illustrated embodiments of our invention in the accompanying drawings wherein:

Fig. 1 is a perspective view of the complete bag formed in accordance with our invention; 70

Fig. 2 is a front elevational view of the bag;

Fig. 3 is an end view thereof;

Fig. 4 is a bottom view thereof; 75

Fig. 5 is a sectional view taken along the line 5—5 of Fig. 4; and

Fig. 6 is a plan view of strips which are illustrative of the component parts which may constitute the bottom of the bag. 80

Upon viewing Figs. 1 and 3 of the drawing, it will be observed that we have shown our invention as embodied in a bag, the mouth or opening of which is defined by a U-shaped rigid frame construction. This 85 frame construction comprises two complementary U-shaped members or frames 10 adapted to lie in coincidence with each other when the bag is closed and pivoted to each other at 19 at the lower end of the depending legs 17 and 18 so that the bag is opened and closed by swinging the frames relatively to each other about said pivots. 90

The side elements 11 of the bag are each in the form of a substantially rectangular 95 piece of material associated in a suitable manner along one longitudinal edge with the top edge 15 of one of the frames 10.

The balance of the bag structure illustrated in the drawings is constituted of a 100 connecting portion which binds the sides 11 together and provides the bottom and ends for the bag and we will term this portion of the bag the "gusset". Where we have made this bottom or connecting portion or gusset of an imperforate blank, we have found that disadvantages result therefrom among which are, (first) that due to the fact that this 105

gusset or bottom must generally be of substantial width so as to provide for the desired bag capacity, the bottom will sag when the bag is loaded and after considerable use, 5 the bottom or gusset will develop a permanent sag; (second) that an imperforate one-piece bottom or gusset permits only of limited variations in its contour.

In accordance with the present invention, 10 we have found that these difficulties can be overcome to a great extent by making this connecting portion so as to break up the continuity of the material across the width of the gusset and one way of attaining this, has 15 been illustrated in the drawings.

Upon viewing Fig. 4 of the drawing, it will be observed that we make our gusset of two component parts which take the form of strips 12 and 13 and which are mutually 20 associated in the manner to be presently described.

Referring to Figs. 3 and 4, it will be observed that each of these strips is of an elongated character whose ends are wider 25 than the rest of the strip. In other words, the longitudinal edges of each strip converge toward the center thereof. Thus, the longitudinal edges which are to be united with the peripheral edges of the sides 11 may be made 30 concave as shown in Fig. 4 and it will be understood that the lengths of these edges are made identical with the peripheral length of the unattached edges of each side 11. When the strips 12 and 13 are associated 35 with each other, they are preferably stitched together along their adjacent edges 14. Each end of each strip is then associated with one element of one arm of the frame 10, and it will now be observed that 40 these end edges of the strips must have a length substantially equal to the lengths of the arms 17 and 18. As a result of this association of the various parts, the sides 11 will have been connected with each other by a 45 composite connecting portion which constitutes not only a bottom for the bag but also ends therefor. It will also be obvious that 50 the seam between the portions 12 and 13 will extend longitudinally of the bottom, and will have its terminal ends in adjacency with the hinge points of which the point is illustrative. The seam will thus serve to break up the effective width of the gusset and thus 55 materially aid in reducing the sag.

In Figs. 1 to 4, we have denoted this seam by the reference numeral 14. It is along this seam that we provide a longitudinal reinforcing rib which prevents distortion of the bottom. We have found it satisfactory 60 to construct this seam in such a manner that the seam itself will constitute the reinforcing rib. This is particularly feasible where the bag is constructed of material such as leather, and we have found it preferable to 65 provide the seam in a manner as shown in

Fig. 5. It will be observed that the strips 12 and 13 are not attached directly to each other, but are attached to a U-shaped connecting rib 23. This rib is so disposed with respect to the completed bag as to have its 70 free ends 24 invisibly positioned in the interior of the bag, and the juxtaposed edges of the strips 12 and 13 are preferably turned inwardly in the same direction before being attached to the rib 23. From the outside, 75 nothing is visible except the small ridge or bead constituted by the closed end of the U-shaped rib 23.

It will be now obvious that the longitudinal reinforcing rib, constituted in the illustrated embodiment by the seam between the strips 12 and 13, will serve to limit the extent to which the bottom may sag. Furthermore, this seam will definitely define the line of folding which is necessarily produced 85 when the bag is closed.

By virtue of our composite structure, we are enabled to achieve results in bag construction which have, to our knowledge, never been achieved before. The composite nature of the bottom and ends permits us to form this portion of the bag in a manner which will impart a predetermined form thereto by designing the component parts of this portion in accordance with a 90 predetermined plan. In Fig. 6 we have illustrated component parts which are illustrative of this feature of our invention. Referring to this figure, it will be observed that we have shown two elongated strips 100 12' and 13' corresponding substantially to the strips 12 and 13 hereinbefore described. The ends 21 of these strips are made substantially equal in length to the length of the arms 17 and 18. The external longitudinal edges 22 are concavely formed, and are of a length to conform substantially to the peripheral unconnected edges of the sides 11. In this embodiment, however, we have constructed the internal or juxtaposed 105 edges 21 of the strips in a manner which makes them similarly concave, thereby producing a gap between the strips when they are initially laid side by side. After the strips have been associated with each other, 110 the edges 21 being stitched or similarly united one with the other, it will be observed that the composite structure will no longer lie in a single plane but will have been deflected and distorted to a certain extent by virtue of the concavity of the edges 21. This distortion will be produced in accordance with a predetermined design, and will render the composite structure particularly effective in enhancing the rigidity and 115 neat appearance of the finished bag. Thus, the composite structure permits us to properly shape this portion of the bag in accordance with particular requirements.

These requirements may vary, depending 120

upon the design of the rigid frame and upon the outline of the sides 11, but by properly designing the component parts 12 and 13, a completed structure can be built 5 up which is extremely pleasing in appearance and which will reflect careful workmanship. It will be obvious that additional component parts may be provided, such as gussets or similar auxiliary elements, depending upon the requirements of the bag 10 from the standpoint of capacity and design. It will also be obvious that many changes 15 in the details herein described and illustrated for the purpose of explaining the nature of our invention may be made by those skilled in the art without departing from the spirit and scope of the invention as expressed in the appended claims. It is therefore intended that these details be interpreted as illustrative and not in a limiting 20 sense.

Having thus described our invention and illustrated its use, what we claim as new and desire to secure by Letters Patent is:—

25 1. In a hand bag, a pair of side elements, and a connecting portion extending around the ends and bottom of the bag between said side elements and attached thereto, said connecting portion including a plurality of strips joined together along their longitudinal edges.

30 2. In a hand bag, a U-shaped rigid frame defining the mouth of the bag, a pair of sides attached to the base of the frame, and 35 a bottom for the bag interposed between

said sides and comprising a plurality of integral U-shaped strips attached at their ends to the arms of the frame and attached to each other along adjacent longitudinal edges.

3. In a hand bag, a U-shaped rigid frame defining the mouth of the bag, a pair of sides attached to the base of the frame, and a bottom for the bag interposed between 40 said sides and including two U-shaped strips attached at their ends to the arms of the frame and attached to each other along adjacent longitudinal edges, said last named edges being connected through the interpolation of a U-shaped connecting rib there- 45 between to which each of said edges is attached.

4. In a hand bag, a composite bottom comprising a plurality of longitudinal strips having concave longitudinal edges, and attached to each other along adjacent longitudinal edges.

5. In a hand bag, a U-shaped rigid frame comprising hinged elements, a pair of sides attached to the base of the frame, and a 50 combined bottom and ends for the bag interposed between the sides comprising a plurality of strips attached at their ends to the arms of the frame and to each other along adjacent longitudinal edges.

In testimony whereof, we have hereunto signed our names.

CHARLES J. McCABE
IRVING SCHOENHOLZ.
